TIME SWITCH

James McCarrol, Toronto, Ontario, and Leonard K. Cheswright, Swansea, Ontario, Canada

Application September 24, 1936, Serial No. 102,294

6 Claims. (CL 200—36)

This invention relates to time switches, and the object of our invention is to devise a simple switch which will make and break an electrical connection at predetermined times and which 5 may be applied to a clock of standard construction.

We achieve our object by means of two cam-like contact members adapted to engage contact fingers for respectively making and breaking the 10 circuit. The contact members are rotated by the clock mechanism and are adjustable relative to one another and the clock mechanism for setting to make and break at the desired time. The switch mechanism is adapted to be quickly and 15 easily applied to a clock of standard construction without altering the mechanism of the clock.

Our invention is hereinafter more particularly described and is illustrated in the enclosed drawing in which

20 Fig. 1 is a rear view of a clock with our switch mechanism applied thereto;

Fig. 2 a side elevation;

Fig. 3 a side perspective view of the plate upon which the switch is mounted;

25 Fig. 4 a cross section on an enlarged scale of the switch mechanism on the line 4—4 in Fig. 1, partly broken away;

Fig. 5 a plan view of the "break" contact member, showing the contact finger about to engage 30 it;

Fig. 6 a plan view of the "break" contact member showing the contact finger immediately after contact has been broken;

Fig. 7 a plan view of the "make" cam showing 35 the contact finger about to make the contact;

Fig. 8 a side elevation of a modified form of contact member and contact finger; and

Fig. 9 a side view of the centre arbor of the 40 clock with the pinion in position to be mounted thereon.

In the drawing like numerals of reference indicate corresponding parts in the different figures.

The switch mechanism is mounted on a plate 45 10 provided with spring fingers 11 adapted to extend between the inner and outer casing of an alarm clock 12 of standard design, or to otherwise detachably engage the exterior of a clock.

The plate 10 is provided with openings as 50 shown in Fig. 1, through which the winding stem 13 may pass, and through which the handsetting shaft 14, speed adjusting lever 15, and the centre arbor 16 are accessible.

Secured to the plate 10 and extending at right 55 angles thereto is a fixed shaft 17 having thereon

a rotatable sleeve 18 of insulating material. The base 18a of the sleeve 18 is enlarged and forms a shoulder. A geared wheel or disc 19 is mounted on the sleeve 18 and bears against the shoulder. The disc 19 is keyed or otherwise fixed relative to 6 the sleeve 18.

A cam-like contact member 20 of brass or similar conducting material is rotatably mounted on the sleeve 18 above the disc 19 and is separated therefrom by a disc 22 of insulating material. A 10 hub 20a extends from the outer side of the contact member 20 and rotatably mounted on this hub is another contact member 21. The contact members 20 and 21 are of reduced diameter for substantially one-half of their periphery. 15

Keyed to the hub 20a of the contact member 20 is a disc 23 of insulating material, and keyed to the contact member 21 is a disc 24 of insulating material.

The outer end 18b of the sleeve 18 is threaded 20 and is reduced in diameter to form a shoulder. A dial 25 bearing time indicia, preferably indicating twenty-four hours, is mounted on the upper end 18b of the sleeve 18 and is clamped on the shoulder non-rotatably and in fixed relation to 25 the disc 19 by means of a knurled nut 26. A coil spring 27 is mounted between the dial 25 and the disc 23, serving to maintain the contact members 20 and 21 in frictional engagement with each other and the disc 19, whereby they may be manually adjusted relative to one another, but normally move in unison. 30

The outer end of the shaft 17 is threaded to receive a cap 28 which retains the switch mechanism above described on the shaft. 35

A pinion 29 is fitted over the centre arbor 16 and is rotatable by the clock mechanism. The pinion 29 meshes with the disc 19 causing it to rotate in synchronism with the clock work. The gearing is such that the disc 19 and hence the 40 dial 25 will rotate once in every 12 hours or once in every 24 hours. The time indicia on the dial 25 represents the hours of one to twelve or one to twenty-four and the dial 25 is mounted in a predetermined position corresponding to the 45 actual time of the day, e. g. as shown in Fig. 1 the time indicia 24 is above the longitudinal axis of the shaft 17 and on the vertical axis of the dial 25 at twelve o'clock noon. The setting of the dial is usually made relative to the time indicated 50 by the clock to which the device is attached, but it may be set by any other clock.

The discs 23 and 24 are provided with pointers 55 and 31 respectively which extend around the edge of the dial 25 and point to the time indicia 56.

thereon. These pointers may be grasped to rotate the contact members 20 and 21 respectively relative to the disc 19 for adjusting the time of making and breaking of the circuit. Contact member 20 is the "break" contact member and if it is desired to break the contact at twelve noon the pointer 30 is rotated until it is opposite the number twelve on the dial 25, as in Fig. 1. The contact member 21 is the "make" contact member and if it is desired to make the contact at twelve midnight the pointer 31 is moved until it is opposite the number twenty-four on the dial 25, as in Fig. 1. The member 32 is merely a handle for turning the "break" contact member when the pointer 30 is beneath the pointer 31.

The actual contact is made with two resilient contact fingers 33 and 34 which are secured to a lug 35 which is secured to the plate 10. The contact fingers are positioned so that they are engaged by the part of the periphery of the contact members 20 and 21 respectively having the larger diameter, and they do not contact with the portion of the periphery of the contact members 20 and 21 having a reduced periphery.

25 Alternatively of course, the portion of the contact members having the reduced diameter might be provided with a filler of insulating material (not shown).

The contact members 20 and 21 are in electrical contact with one another so that when both engage the contact fingers 33 and 34 a circuit is completed between the contact fingers. Terminals 36 and 37 are provided on the contact fingers 33 and 34, respectively, to which may be connected electric wires 38 and 39. A fuse may be inserted in the circuit. A plug 40 for connecting a lighting or heating device in the circuit is provided.

To effect a rapid making of contact a pin 41 of insulating material may be provided extending from the periphery of the contact member 21, whereby the contact finger 34 is raised slightly and then permitted to drop comparatively rapidly into contact with the periphery of the contact member 21 thus providing a quick "make" and minimizing arcing. (See Fig. 7.)

To effect a rapid and clean breaking of contact the periphery of the contact member 20 may be undercut (see Figs. 5 and 6).

50 A better contact with less friction may be obtained by forming a groove in the periphery of the contact members and providing a wheel in the ends of the contact fingers as illustrated in Fig. 8. The undercut periphery of the contact member 20 as described in the next preceding paragraph is particularly useful in combination with the construction of contact fingers and contact members described in this paragraph.

A suitable insulated cover 42 (illustrated in dotted lines in Fig. 1) may be provided to cover the contacts.

The device illustrated is so constructed that the longest period that the circuit can be closed is twelve hours, but it is obvious that the construction can be varied to provide for closing the circuit for a period up to twenty-four hours.

To use the device, the dial 25 is first set to agree with the actual time of the clock. This may be done by loosening the nut 26 and rotating the dial so that the position of the numbers on the dial corresponds with the position of the hour hand on the clock (not shown). A convenient method of setting is to move the hands of the clock by means of the setting shaft 14 to twelve o'clock noon and set the dial 25 with the numeral

representing twelve o'clock directly above the axis of the shaft 17, as shown in Fig. 1. The dial can then be secured from rotation by screwing down the nut 26 and the clock can then be set to the actual time and the dial will move in unison therewith.

To set the time switch to the desired time for making and breaking the contact the pointers 30 and 31 are moved to point to the desired time on the dial, care being taken to set the time switch 10 so that the period for which the circuit is made is not more than twelve hours.

What we claim as our invention is:

1. A time switch, comprising time clock mechanism; a pair of electrically connected cam-like contact members continuously rotatable by the clock mechanism and adjustable relative to one another; and a pair of contact fingers each adapted to be engaged by the periphery of one of said contact members during a part only of their rotary movement.

2. A time switch, comprising time clock mechanism, a disc rotatable by the clock mechanism; a dial associated with the disc, bearing time indicia; a pair of electrically connected cam-like contact members continuously rotatable with the said disc and adjustable relative thereto to respectively make and break a circuit at predetermined times as designated on the dial; and a pair of contact fingers each adapted to be engaged by the periphery of one of said contact members during a part only of their rotary movement.

3. A time switch comprising time clock mechanism; a disc continuously rotatable by the clock mechanism; a "make" contact member; a "break" contact member, said contact members being in frictional engagement with one another and the disc whereby they normally rotate with the disc but may be manually rotated relative to each other and the disc for time adjustment; and a pair of contact fingers, one of which is engaged by the periphery of the "make" contact member through part of its rotary movement and the other of which is engaged by the "break" contact member through part of its rotary movement, whereby when both fingers are simultaneously engaged by the contact members the circuit is made and when one of them is out of engagement with its corresponding contact member the circuit is broken.

4. A time switch comprising clock mechanism, including a spindle which rotates once in a predetermined period of time such as the centre arbor; a shaft; a disc rotatably mounted on the shaft; two cam-like contact members rotatably mounted on the shaft; a dial bearing time indicia mounted on the shaft and fixed relative to the disc; a spring tending to retain the contact members in frictional engagement with each other and the disc whereby they normally rotate with the disc and the dial but are adjustable relative thereto; a pointer connected to each of the contact members and adapted to point to time indicia on the dial, the disc being so geared and the dial so calibrated and set that when the pointer on one of the contact members points to a selected time on the dial the circuit will make at that time and when the pointer of the other contact member points to a selected time the circuit will break at that time; and two contact fingers each adapted to engage the raised portion of the periphery of each contact member as it rotates.

5. A time switch comprising clock mechanism, a casing for said clock mechanism; an hour hand

spindle extending through the casing; a plate; fingers on the plate adapted to detachably engage the casing of the clock mechanism; an opening in the casing; a pinion adapted to be mounted on the hour hand spindle and extend through the opening in the casing; a shaft on the casing; a geared disc on the shaft meshing with the pinion on the hour hand spindle; contact members mounted on the shaft and rotatable with the disc; and contact fingers adapted to be engaged by the said contact members.

6. A time switch, comprising time clock mechanism, including a centre arbor, a pinion on the centre arbor; a geared disc meshing with and

rotatable by the pinion; a dial rotatable with and in fixed relation to the disc and bearing time indicia thereon; two cam-like contact members normally rotatable with the disc but adjustable relative thereto and to the dial; means on the 5 contact members for adjusting their position relative to the time indicia on the dial to set the contact members respectively for the time desired for making and breaking the circuit; and contact fingers adapted to engage the said contact members during a part only of their rotary movement.
